Inventor:

UNITED STATES PATENT OFFICE.

ULYSSES GRANT LEE, OF CHATTANOOGA, TENNESSEE, ASSIGNOR TO MONTAGUE
MAILING MACHINERY COMPANY, A CORPORATION OF TENNESSEE.

ADDRESSING-MACHINE, (COUPON-BILLS.)

1,122,286.

Specification of Letters Patent. Patented Dec. 29, 1914.

Application filed April 15, 1912. Serial No. 690,905.

To all whom it may concern:

Be it known that I, ULYSSES GRANT LEE, a citizen of the United States, residing at Chattanooga, Tennessee, have invented certain new and useful Improvements in Addressing-Machines, (Coupon-Bills,) of which the following is a specification.

It is the object of my invention to provide a machine for printing public service bills or the like, having attached one or more coupons, such machines being constructed to handle and print from address plates which bear the address thereon, and which move from point to point to make the impression on the bill at different places thereon as may be desired.

The invention is shown in the accompanying drawings, in which—

Figure 1 is a perspective view of a part of an addressing machine embodying my invention; Fig. 2 is a sectional view with parts in elevation.

The address plates employed are those used in the Montague system. These address plates are fed by means of a suitable carrier which may consist of a chain having feed dogs 1 thereon, as shown in Fig. 1, to move the address plates, one of which is shown at *a*, along the channel or way 2, in the bed of the machine. This feed chain and the method of operating it step by step does not specifically form a part of my present invention. The chain may be operated, and the address plates guided in substantially the same manner as is disclosed in Letters Patent of the United States Patent Office No. 1,012,424, granted December 19, 1911, to Owens, Lee and Lyle. The general arrangement of the impression block or cross head may also be substantially the same as that disclosed in said patent, consisting of the cross-bar 3, connected with end frames 4, carried by rods 5 suitably guided in the frame of the machine and reciprocated vertically in any suitable manner. The cross-bar 3 carries the impression pads 6, 7 and 8. These impression pads are arranged each over the pathway along which the address plates must move step by step. The organization is such that when the address plate arrives under the impression pad 6 the cross head 3 moves downwardly to make the impression on the bill or other sheet being printed, it being understood that the sheets or bills to be printed are fed

transversely of the guideway of the address plates and against stops, one of which is shown at A in Fig. 2. The sheets are fed in the direction of the arrow in said figure, by means of feed tapes. These tapes are illustrated at 9, 10. A suitable inking ribbon is also employed, such as in the patent above referred to, and extending over the guideway for the address plates, and beneath the impression pads. The impression pads are located in relation to each other, and to the feed of the address plates, so that step by step movement of the address plate will cause it to assume a position first under one impression pad and then under the next 70 impression pad, and so on throughout the series, the address plate making an impression in connection with each impression pad, so that with a bill having two coupons attached the main portion of the bill and also 75 each coupon may be printed. Of course the impression pads may be arranged differently from what is shown in the drawings and need not occupy positions corresponding to the consecutive or successive positions 80 of the address plate.

It will be understood that the stops A hold the sheet while being printed upon and after the printing is done the sheet is moved onward and its place taken by another 85 sheet.

It will be understood that while I have shown the best means now known to me for carrying out my invention, I do not wish to limit myself to the precise way disclosed, 90 this being representative of any suitable means for carrying out the general principles of my invention, the broad principle of which is changing the relation between the sheet to be printed and the address plate to 95 make impressions at different points on the sheet.

The rock shaft B carrying stops A is operated by a cam C. This cam is mounted on a sleeve running on a pin D. This sleeve 100 is geared to a shaft E on a ratio of three to one when a three print is desired.

The cam operates the lever F by means of a roller G. Lever F, is connected by means of link H, to a lever I secured to shaft J. 105 Lever K is mounted on said shaft J, and is connected by means of a link L, to a lever M, mounted on the rock shaft B.

The several impression pads are attached to the impression bar 3, and as these are 110

separate from each other, as shown, the impression head can be varied as to this extent by removing one or more of these pads or the pads may be set at different points 5 along the bar. When a single impression head is employed, an impression can be taken from this head at each stroke, and at each action of the plate feed mechanism, in which event each plate feed action would 10 bring a new record plate beneath this impression head, the plates being then disposed at each of the feed dogs on said feed mechanism. The drawing, however, shows the machine organized with plates disposed at 15 every third feed dog, the other two feed dogs being empty.

I claim as my invention:—

1. In an addressing machine, the combination of a series of record or address plates, 20 an impression member, a feeder for the record plates having dogs regularly spaced apart to engage the plates and move them a definite distance at each feeding action, said impression member being disposed over a 25 number of spaces between the dogs and said record plates being disposed at intervals on the feeder leaving some of the dogs empty whereby a plurality of impressions may be taken from the same plate while passing under the impression head, substantially as described.

2. In an addressing machine, the combination of an impression member, a support for address plates and articles to receive the 35 impression, with feeding means for changing the relation between the address plate and said article to make a plurality of impressions in succession from the address plate, the lines of printing in said impressions from the same record plate being longitudinally in alinement across the article, substantially as described.

3. In an addressing machine, the combination of an impression member, a support 45 for address plates and articles to receive the impression, with feeding means for changing the relation between the address plate and said article to make a plurality of impressions in succession from one address 50 plate, the lines of printing in said impressions being longitudinally in alinement across the article, substantially as described.

4. In an addressing machine, the combination of an impression member, a table 55 having a runway for address plates, a feeder for said address plates to move the same

along the table, a feeder for articles to be addressed, one of said feeders being ineffective to allow the article fed thereby to remain at rest while the other feeder performs 60 its cycle of plural actions to secure successively a plurality of impressions from the same address plate upon the same article, substantially as described.

5. In combination in addressing machinery for imposing addresses on members from address carrying members, impression means, feeding means for one set of said members moving them step by step, and holding means for the other set of said members to hold each stationary during the making of plural impressions in succession on the member to be addressed, substantially as described.

6. In combination, impression means, an 75 address plate feeder, holding means for the article to be addressed for retaining the same in one position while receiving plural impressions, said address plate feeder moving the plate step by step from one part of the 80 impression means to another for making plural impressions in succession from the same plate on the same article, said plates being spaced apart on the feeder distances equal to or greater than the length of the 85 step movements of the feeder, substantially as described.

7. In an addressing machine, the combination of a series of record or address plates, an impression member having a plurality of 90 impression pads individually removable and adjustable to different positions along the impression member, a plate feeder to move the record plates lengthwise of the impression member and beneath the impression 95 pads, said feeder having dogs regularly spaced apart to engage the plates and move them a definite distance at each feeding action, said impression member being disposed over a number of spaces between the dogs, 100 and said record plates being disposed at intervals on the feeder leaving some of the dogs empty, whereby a plurality of impressions may be taken from the same plate at various points while passing under the impression member.

In testimony whereof, I affix my signature in presence of two witnesses.

ULYSSES GRANT LEE.
